CLAIM

The ornamental design for a two-part quick release device for electronic game steering wheels, as shown and described.

DESCRIPTION

The patent or application file contains at least one drawing executed in color. Copies of this patent or patent application

publication with color drawing(s) will be provided by the Office upon request and payment of the necessary fee.

1. Two-part quick release device for electronic game steering wheels

1.1 : Perspective view of a first part of the two-part quick release device for electronic game steering wheels.

1.2 : Left view of the first part of the two-part quick release device for electronic game steering wheels shown in 1.1.

1.3 : Perspective view of the first part of the two-part quick release device for electronic game steering wheels shown in 1.1.

1.4 : Front view of the first part of the two-part quick release device for electronic game steering wheels shown in 1.1.

1.5 : Back view of the first part of the two-part quick release device for electronic game steering wheels shown in 1.1.

1.6 : Top view of the first part of the two-part quick release device for electronic game steering wheels shown in 1.1.

1.7 : Bottom view of the first part of the two-part quick release device for electronic game steering wheels shown in 1.1.

2.1 : Perspective view of a second part of the two-part quick release device for electronic game steering wheels.

2.2 : Top view of the second part of the two-part quick release device for electronic game steering wheels shown in 2.1.

2.3 : Front view of the second part of the two-part quick release device for electronic game steering wheels shown in 2.1.

2.4 : Back view of the second part of the two-part quick release device for electronic game steering wheels shown in 2.1.

2.5 : Left view of the second part of the two-part quick release device for electronic game steering wheels shown in 2.1.

2.6 : Perspective view of the second part of the two-part quick release device for electronic game steering wheels shown in 2.1.

2.7 : Bottom view of the second part of the two-part quick release device for electronic game steering wheels shown in 2.1.

3.1 : Front view of the two-part quick release device for electronic game steering wheels.

3.2 : Left view of the two-part quick release device for electronic game steering wheels shown in 3.1.

(Continued)

- 3.3** : Perspective view of the two-part quick release device for electronic game steering wheels shown in **3.1**.
3.4 : Bottom view of the two-part quick release device for electronic game steering wheels shown in **3..**
3.5 : Top view of the two-part quick release device for electronic game steering wheels shown in **3.1**.
3.6 : Back view of the two-part quick release device for electronic game steering wheels shown in **3.1**.
3.7 : Perspective view of the two-part quick release device for electronic game steering wheels shown in **3.1**.
